PROPELLER FEATHERING CONTROL

Erle Martin, West Hartford, Conn., assignor to
 United Aircraft Corporation, East Hartford,
 Conn., a corporation of Delaware

Application October 27, 1939, Serial No. 301,539

5 Claims. (Cl. 121—38)

1

This invention relates to improvements in propeller control means and has particular reference to an improved means for controlling the feathering and unfeathering operations of a hydro-controllable propeller.

An object of the invention resides in the provision of improved means for controlling the application of hydraulic fluid under pressure to a hydro-controllable propeller to feather or unfeather the same in such a manner that the application of the hydraulic fluid under pressure will be discontinued when the feathered or unfeathered condition of the propeller is reached.

A further object resides in the provision of an improved control of the character indicated which is responsive to a physical characteristic of the hydraulic fluid such as the pressure or rate of flow to control the feathering and unfeathering operations of the propeller.

A still further object resides in the provision of a hydraulic propeller control of the character indicated which is small and compact so that it may be installed in the cockpit within easy reach of the pilot without taking up an unreasonable amount of space and which requires no further attention from the pilot once it has been set to bring about the propeller position desired.

Other objects and advantages will be more particularly pointed out hereinafter or will become apparent as the description proceeds.

In the accompanying drawings in which like reference numerals are used to designate similar parts throughout there is shown a suitable mechanical construction for the purpose of disclosing the invention and one somewhat modified form thereof. The drawings, however, are for the purpose of illustration only and are not to be taken as limiting or restricting the invention since it will be apparent to those skilled in the art that various changes in the illustrated constructions may be resorted to without in any way exceeding the scope of the invention.

In the drawings,

Fig. 1 is a somewhat diagrammatic view of the pitch control mechanism for a controllable pitch propeller, the improved feathering and unfeathering control valve included therein being shown partly in section to better illustrate the construction thereof.

Fig. 2 is a diagrammatic view of a hydro-controllable pitch propeller of a type to which the improved control valve is particularly applicable.

Fig. 3 is a view of the propeller fluid distributing valve illustrated in Fig. 2, the valve being

2

shown in a different operative position in Fig. 3 than the position illustrated in Fig. 2.

Fig. 4 is a vertical sectional view through an improved pitch control valve constructed according to the invention.

Fig. 5 is a vertical sectional view through a somewhat modified form of propeller pitch control valve, and

Fig. 6 is a fragmentary view similar to a portion of Fig. 5 showing the valve parts in a different operative position.

Referring to the drawings in detail, the numeral 10 generally indicates a hydro-controllable propeller, the pitch of which is controlled in the normal or constant speed range by a governor, generally indicated at 12, and which may be brought into and out of a feathered position by the feathering control valve generally indicated at 14.

15 The propeller may be such a propeller as is more particularly illustrated and described in my co-pending joint application Serial No. 184,792, filed January 13, 1938, for Feathering propeller control, issued on April 21, 1942, as U. S. Patent No. 2,280,714, and may comprise in general, a plurality of blades, as indicated at 16, rotatably mounted at their root or base ends in a hub structure 18 and rotatable about their longitudinal axes by a gear element 20 which is rotated 25 through a cam 22 by means of a piston 24 reciprocable in the cylinder 26.

20 The propeller is mounted upon a drive shaft 28 which contains the distributing valve, generally indicated at 30. When the distributing valve is in position for constant speed control by the governor 12, as illustrated in Fig. 2, the conduit 32, leading from a suitable source of hydraulic fluid under pressure such as the engine lubricating pump 34, is connected through the 25 valve passages 36 and 38 and the conduit 40 with the space between the piston 24 and the closed outer end of the cylinder 26 to exert a continuous force on the piston 24 to assist the action of centrifugal force acting on the blades 16 to turn the blades towards their low pitch position.

30 A second channel 42, which may be the space within the hollow shaft 28 surrounding the tube or conduit 32, is connected through the oil collector ring 44 and the associated passages with a governor controlled valve, not illustrated, and leads 35 through the valve passages 46 and 48 and the conduit 50 to the space at the end of the piston 24 adjacent to the hub 18. The governor controlled valve is connected with a source of hydraulic fluid under pressure, such as the booster

40

45

50

55

pump 52, which increases the pressure produced by the pump 34, and is also connected with a drain line 56 and is capable of connecting the channel 42 either with the high pressure fluid source or with the drain line depending upon the demands of the speed responsive governor 12 for a higher or a lower propeller pitch. If the engine speed is too high, the governor will connect the channel 42 with the high pressure fluid source to increase the propeller pitch, and if the speed of the engine is too low, the governor will connect the channel 42 with the drain line 56 to permit the propeller pitch to decrease under the action of centrifugal force and the fluid pressure supplied through the conduit 40, to correspondingly change the load on the engine and increase the engine speed.

The valve 14 is connected at one side through the conduit 58 with a source of hydraulic fluid under a pressure higher than the pressure output of the pump 52, which source has been diagrammatically represented as the pressure tank 60 which may be supplied with fluid under pressure through the conduit 62 leading from a pump or other suitable source. The valve is connected at the same time through the conduit 64 to the sump or reservoir 66. At its opposite side the valve is connected through the conduit 68 to the control valve, generally indicated at 70, which is in turn connected with the governor actuated valve through the channel 72 and with the slip ring 44 through the channel or conduit 74. The valve 70 may be such as is particularly illustrated and described in my co-pending application Serial No. 274,334, filed May 18, 1939, for Propeller pitch control valve, issued on June 24, 1941, as U. S. Patent No. 2,246,745, and is operative to connect the governor channel 72 with the line 74 to simultaneously block the conduit 68 from the governor and propeller pitch control conduits, when the fluid pressure in line 68 is not sufficient to open the valve. This valve also acts to cut off the channel 72 from the channel 74 and connect the valve line 68 with the line 74 and collector ring 44 when the pressure in the line 68 exceeds the pressure developed by the governor pump 52, by an amount sufficient to open the valve.

For a detailed description of the valve 14 reference may now be had to Figs. 4, 5 and 6.

Considering first the form of valve shown in Fig. 4, the fluid pressure line 58 from the pressure source 60 leads to a chamber or bore 76 extending through the valve casing 78 which chamber is connected by the transverse passage 80 to the parallel bore or chamber 82 from which the line 68 leading to the propeller extends. A valve stem 84 in the chamber 76 cooperates with a valve seat 86 to separate the pressure line 58 from the transverse passage 80, the valve being urged into seating relation by the compression spring 88 supported in the enlarged lower end of the chamber 76. The valve may be actuated by a plunger 90 which extends through a gland nut 92 threaded into the upper end of the chamber 76, and is operatively connected, by suitable means, such as the pivoted links 94, with a hand lever 96. When the lever 96 is forced down manually the plunger 90 contacts the upper end of the valve stem 84 and moves the valve stem downwardly against the force of the spring 88 to unseat the plunger from the seat 86 and open the valve, thereby connecting the pressure line 58 with the transverse passage 80 and chamber 82. The lever 96 is urged upwardly by a suitable

means, such as the spring 98, and may be latched in its downward position by the latch 100 cooperating with the pin 99. This latch may be manually disengaged by swinging the outer portion of the lever upwardly about the pivot 101 to move the tongue 102 against the hook 100 and force the lock out of engagement with the pin. When the valve 84-86 is open, the fluid under pressure will flow through the conduit 58, through the valve and through the transverse passage 80 into the chamber 82 where it will act against the undersurface of the piston 104 carried by the stem 106 reciprocably mounted in the chamber 82 and projecting at its upper end through the gland nut 108'. The piston 104 is slightly smaller than the chamber 82 in which it is located to provide a restricted passage between the piston and the wall of the chamber, and is urged downwardly toward the limiting position illustrated in Fig. 4 by the compression spring 108. Fluid under pressure, flowing from the pressure line 58, through the valve 84-86 and through the transverse channel 80, flows between the piston 104 and the wall of the chamber 82 to the upper part of the chamber and to the conduit 68, incidentally pressing the piston 104 upwardly against the force of the spring 108 because of the restriction provided between the piston 104 and the chamber wall. It is apparent that when the propeller is being feathered or unfeathered, this flow will continue as long as the piston 24 continues to move in the same direction. As soon as the piston reaches its limiting position, the flow will stop whereupon the pressure upon the opposite sides of the piston 104 will become equalized and the spring 108 will push the piston downwardly again to the position illustrated in Fig. 4. Upon its end extending through the gland nut 108', the stem 106 carries an abutment 110 which cooperates with a pin 111 carried by the latch 100 to move the latch clear of the pin 99 when the piston 104 moves downwardly, thereby releasing the hand lever 96 and permitting the spring 88 to close the valve 86 and discontinue the supply of pressure fluid to the propeller.

The plunger 90 is provided, on its inner end, with a valve 112 which cooperates with a valve seat formed in the upper end of the plunger 84 and connected through the channel 114 with the portion of the chamber 76 intercepted by the transverse channel 80 so that, when the hand lever 96 is in its upper position, as illustrated, the channel 80 is connected through the channel 114, valve 112, port 116 and drilled channels 118 and 120 with the drain line 64 to relieve the fluid pressure in the propeller pitch changing mechanism and in the valve 14 and the connecting line 68 after the propeller has been brought to its feathered position and the handle 96 released by the trip mechanism including the abutment 110, pin 111 and the latch 100. The spaces at the lower ends of the stems 84 and 106 are continuously connected with the drain line through the drilled channels 122 and 124 and the ports 126 so that movements of these plungers will not be affected by fluid trapped in the closed ends of the respective chambers and the ends of the movable stems.

In the form of valve shown in Figs. 5 and 6 the arrangement of the control valve 84, spring 88, plunger 90, link 94, hand lever 96 and spring 98 is substantially the same as that described above. In this modified form of invention, however, a pressure responsive valve generally indi-

cated at 128 is mounted in a chamber 130 which extends only partly through the valve casing 78 and is hydraulically disposed between the pressure line 58 and the chamber 76 containing the valve 84. When the handle 96 has been forced down and caught by the latch 132 the valve 86 will be open and the hydraulic fluid under pressure will flow from the pressure line 58 through the valve 86 to the fluid conduit 68 leading to the propeller. The channel 125 will apply the fluid pressure to the valve 128 to open this valve and move the plunger 134. While the pitch changing piston 24 is moving the increasing capacity of the space between the piston and the respective end of the cylinder 26 will prevent a rapid increase of the fluid pressure in the valve 14. As soon, however, as the piston stops, upon reaching its limiting position, the fluid pressure in the valve will immediately build up and force the plunger 134 and the valve 128 upwardly against the force of the compression spring 136. The upper end of the plunger 134 projects through the gland nut 138 and, upon upward movement of the plunger, will contact a portion 140 of the latch 132 and move the latch to release the hand lever 96 thereby closing the valve 86 and connecting the propeller supply line 68 with drain through the valve seat formed on the upper end of the plunger 84 and the drain line 64, the drain being cut off by the valve 112 and the end of the plunger 90 when the lever 96 is down, as is particularly illustrated in Fig. 6. In the modified arrangement the space below the plunger 84 is connected with drain by means of the ports 142 and the drilled channels 144 and 146.

In bringing the propeller to its feathered position, the propeller distributing valve 30 does not materially change its position since the necessary operation is to increase the pitch of the propeller by supplying high pressure fluid to the rearward or pitch increasing side of the piston 24 which is the same side of the piston to which the governor actuated valve is connected. In order to feather the propeller the hand lever 96 is simply forced inwardly toward the valve casing 78 to apply the high pressure fluid from the source 60 to the above described side of the piston 24. The increase of fluid pressure in the line 68 will move the valve 70 to close off the governor channel 72 and connect the conduit 68 with the conduit 74 which connects with the collector ring 44 which in turn leads through the channel 42 to the distributing valve 30 which, in the position shown in Fig. 2, causes the high pressure fluid to be applied to the left hand end of the piston 24 to increase the propeller pitch, the space of the right hand end of the piston 24 being connected with the engine lubricating system through the conduit 40 so that fluid from this space may be vented through the lubricating system and the pressure release valve 148. As soon as the propeller has reached the feathered position, the hand lever will be released and the space at the left hand end of the piston 24 connected with drain, as described above, to relieve the fluid pressure on the piston and the connecting conduit. At the same time flow of fluid from the pressure source 60 will be blocked by the closing of the valve 86.

When it is desired to return the propeller from its feathered position to the range in which it is under the control of the governor 12, the hand lever 96 must again be forced down to render the valve 14 operative to supply additional pressure fluid to the propeller. Since the fluid pressure required to unfeather the propeller is greater

than the pressure required to bring the propeller to a feathered position, the increased fluid pressure acting on the left hand end of the stem 150 of the distributing valve 30 will move the stem 150 against the force of the compression spring 152 to the position shown in Fig. 3 in which the channel 42 is connected by the valve passages 46 and 48 with the conduit 40 leading to the space at the pitch reducing end of the piston 24, and the conduit 42 is connected through the valve passages 36 and 154 and conduit 50 with the space at the pitch increasing side of the piston 24, thereby reversing the application of the pressure fluid to the pitch changing piston.

If a valve of the kind shown in Figs. 5 and 6 is used, the handle 96 will have to be manually depressed until the propeller blades are started out of their feathered position after which the propeller will start to rotate or windmill and the action of centrifugal force on the blade plus the pressure of the fluid supplied through the conduit 40 will quickly reduce the pitch to the constant speed range. The lock 132, however, will not be operative to hold the lever 96 down because the unfeathering pressure is sufficient to compress the spring 136 and move the plunger 134 upwardly to maintain the latch in an inoperative position.

If the form of valve shown in Fig. 4 is used, the latch 100 will be operative since it will not be disengaged by the abutment member 110 until the fluid flow through the propeller shall have been started and stopped again. With this form of valve the handle 96 would be locked down to bring the propeller out of the feathered position 35 and would be retained in its downward position to hold the valve 86 open until the piston 24 had reached its limiting low pitch position at which time flow of pressure fluid from the source 60 to the propeller would be stopped and the latch 40 mechanism would act to release the lever and close the valve 86 and open the valve 112 thereby relieving the pressure in the line 68 and permitting the valve 70 to change the connection of the line 74 from the line 68 to the channel 72 and restore the propeller to governor control.

While a complete propeller control system has been somewhat diagrammatically illustrated, and two somewhat different forms of propeller feathering and unfeathering control valves have been particularly illustrated, and hereinabove described for the purpose of disclosing the invention, it is to be understood that the invention is not limited to the particular constructions so illustrated and described, but that such changes in the size, shape and arrangement of the various parts may be resorted to as come within the scope of the subjoined claims.

Having now described the invention so that others skilled in the art may clearly understand the same, what it is desired to secure by Letters 60 Patent is as follows:

1. A control including a body formed with inlet and outlet openings and a discharge opening, and passages connecting the same, a valve interposed 65 between said inlet and outlet openings and co-operable with a seat to prevent a flow of fluid from one opening to the other, a sealing portion coupled to said valve and formed with an opening through its body, such opening affording communication between said outlet opening and said discharge opening, a further valve body normally spaced from and movable into contact with said sealing portion to seal the opening therethrough, means coupled to said further valve to cause the 70 same to engage said portion to move the valve 75

connected to said portion to a position such that fluid may flow from said inlet to said outlet opening, said body being formed with a bore, a piston slideable within said bore, said bore being coupled to said passages at a point beyond said first named valve and means controlled by said piston to render said last named means inoperative.

2. A control including a body formed with inlet and outlet openings and a discharge opening, and passages connecting the same, a valve interposed between said inlet and outlet openings and cooperable with a seat to prevent a flow of fluid from one opening to the other, a sealing portion coupled to said valve and formed with an opening through its body, such opening affording communication between said outlet opening and said discharge opening, a further valve body normally spaced from and movable into contact with said sealing portion to seal the opening therethrough, means coupled to said further valve to cause the same to engage said portion to move the valve connected to said portion to a position such that fluid may flow from said inlet to said outlet opening, a latch engageable with said last named means to retain the same against movement, said body being formed with a bore, a piston slideable within said bore, means connected to said piston and engageable with said latch to render the latter inoperative and said bore being connected to a passage within said body at a point beyond said first named valve.

3. A control including a body formed with inlet and outlet openings and a discharge opening, and passages connecting the same, a valve interposed between said inlet and outlet openings, and cooperable with a seat to prevent a flow of fluid from one opening to the other, a sealing portion coupled to said valve and formed with an opening through its body, such opening affording communication between said outlet opening and said discharge opening, a further valve body normally spaced from and movable into contact with said sealing portion to seal the opening therethrough, means coupled to said further valve to cause the same to engage said portion to move the valve connected to said portion to a position such that fluid may flow from said inlet to said outlet opening, a latch engageable with said last named means to retain the same against movement, said body being formed with a bore, a piston slideable within said bore, means connected to said piston and engageable with said latch to render the latter inoperative, said piston being formed with a passage, a valve for controlling the flow of liquid to the base of said piston, said piston-receiving bore being connected to said discharge opening and said bore being also connected by a passage within said body to a point beyond said first named valve.

4. Means for controlling the operation of a hydraulic motor comprising, a pressure responsive reversing valve in the connection between a source of high pressure hydraulic fluid and said motor and operable to change the connection from one side of said motor to the other side when the pressure of said fluid on said valve exceeds a predetermined amount, a control valve in said connection between said reversing valve and said source, manually operable means for opening said control valve and releasable means for holding said control valve open, and means responsive

to a change, downstream of said control valve, in the force producing properties of said motor operating fluid and incident to positioning said motor at its terminal position for preventing reversal of said motor comprising, means automatically releasing said holding means and closing said control valve when said motor reaches a terminal position, said releasing means being actuatable by a change in the force producing properties of said motor operating fluid insufficient to operate said reversing valve.

5. A fluid supply control comprising, a casing having a fluid inlet and a fluid outlet connection, a valve in said casing between said connections, 15 a spring urging said valve to closed position, manual means for opening said valve, means for releasably holding said valve open, means responsive to a change in a characteristic of the fluid flowing through said valve to release said holding 20 means, such change in the fluid characteristic being due to a rise in pressure in said outlet connection, a fluid directing valve connected with said fluid outlet for directing the fluid from said outlet to either of two discharge lines and operable by an increase in the fluid outlet pressure 25 above a preselected value to disconnect one discharge line and connect the other discharge line with said outlet, said means to release said holding means being operative to render said spring effective to close said valve when the fluid pressure in said outlet connection exceeds a predetermined value less than said preselected value and thus prevent said directing valve from changing discharge lines.
